SOLID STATE LOGIC LEARNING CENTER

Daniel M. Flynn, Hampden, Stanley J. Bandoski, Jr., Springfield, and William R. Clow, Agawam, Mass., assignors to Hampden Engineering Company, East Longmeadow, Mass.

Filed July 28, 1970, Ser. No. 24,179

Term of patent 14 years

Int. Cl. D19—07

U.S. Cl. D25—1

FIG. 2

FIG. 3

FIG. 4

FIG. 5

FIG. 6

FIG. 7

FIG. 1 is a front elevational view of the solid state logic learning center.

FIG. 2 is a reduced scale top view of the solid state logic learning center.

FIG. 3 is a reduced scale left-hand end elevational view of the solid state logic learning center.

FIG. 4 is a reduced scale front elevational view of the solid state logic learning center with certain elements and indicia omitted due to their illegibility in extremely small scale reproduction.

FIG. 5 is a reduced scale right-hand end view of the solid state logic learning center.

FIG. 6 is a reduced scale bottom view of the solid state logic learning center.

FIG. 7 is a reduced scale rear view of the solid state logic learning center.

We claim:

The ornamental design for a solid state logic learning center, as shown and described.
